UNITED STATES PATENT OFFICE.

IRA STEVENS, OF SAN JOSÉ, CALIFORNIA, ASSIGNOR OF ONE-HALF TO
JOHN B. STOCKLIN, OF SAME PLACE.

FRUIT-LADDER.

SPECIFICATION forming part of Letters Patent No. 284,920, dated September 11, 1883.

Application filed July 3, 1883. (No model.)

To all whom it may concern:

Be it known that I, IRA STEVENS, a citizen of the United States, residing at San José, in the county of Santa Clara and State of California, have invented certain new and useful Improvements in Fruit-Ladders, of which the following is a specification, reference being had therein to the accompanying drawings.

My invention relates to an improvement in fruit-ladders, especially such as are employed for orchards and other agricultural purposes; and it consists in the adjustable prop A, hoop H, in connection with rack K and steps C, in the method of construction shown, to render the ladder reliable and safe as against accidents arising from its use, and in the combination and arrangement of the parts, substantially as hereinafter more fully shown and described.

20. In the drawings, Figure 1 is a side elevation. Fig. 2 is a rear elevation, and Figs. 3, 4, and 5 are detail views.

In carrying out my invention I construct the ladder gradually enlarged from top to bottom, the lower part of the ladder being much wider than its upper part, to render it less liable to tilt, and as a means of still further securing it against tilting to the right or left the standards of the ladder respectively may, 25 near the bottom thereof, be supplied on either side with a sharp-pointed bolt, to be forced into the ground or floor when necessary. The plane of each step is formed as shown in Fig. 3, a portion thereof being projected between 30 the standards, and each step is fully secured

from breaking by a low riser, R, secured under the forward edge thereof, (see Fig. 1,) which supports it, and which is let into slight corresponding indentations formed in the standards. (See Fig. 3.)

The prop A is hinged to the platform of the ladder, and has rigidly secured thereto the rack K and the sharp-pointed bolt A', the rack being designed, in connection with the loosely pivoted hoop-clutch H, for holding the ladder-prop, when in use, at any angle, as shown in Fig. 1, and the bolt being designed for lengthening the prop, in order to adjust the platform of the prop near to the wall or object to be reached, while also securing the prop and ladder steadfastly in position. The ends of the hoop-clutch H are bent at right angles and projected through the step-standards S, and then nutted to secure them in position.

What I claim is—

1. A step-ladder having its step portion tapering from top to bottom, and its steps secured from breaking by risers R under the forward edge thereof, substantially as shown and described.

2. The combination of the rack K, hoop H, and step portion of the ladder C, substantially as and for the purpose described.

In testimony whereof I affix my signature in presence of two witnesses.

IRA STEVENS.
